VALVE FOR PUMPS

Robert P. Miller, San Gabriel, Calif.

Application May 13, 1940, Serial No. 334,856

5 Claims. (Cl. 103—234)

This invention relates to automatic pumping of fluid by fluid pressure; the present invention being a continuation in part of my copending application Ser. No. 224,887, filed August 15, 1938. The fluid which is to be pumped is herein referred to as production fluid; and the fluid under pressure which pumps the production fluid is herein referred to as displacement fluid.

The invention is particularly applicable to petroleum wells in which the production fluid comprises gaseous and/or liquid constituents, and the liquid constituents are oil and/or water. The displacement fluid may be any suitable gas under pressure supplied from any desired source. In practice, flow tubing for production fluid may extend through usual well casing to the production zone of the well, with displacement fluid supplied via the annular space between the tubing and the surrounding casing, or the flow tubing may surround an inner conduit through which displacement fluid is supplied.

The invention is applicable to that type of pump in which a foot valve controls admission of production fluid to the flow tubing, and a head valve controls admission of displacement fluid for elevating the previously admitted production fluid. Pumping is automatic, the head and foot valves being dependently actuated and alternately opened and closed responsive to pressure differential. At the start of the filling period, pressure in the flow tubing is relieved by discharge of an elevated slug of production fluid so that formation pressure exceeds pressure in the tubing string and thus creates pressure differential for opening the foot valve and closing the head valve. Production fluid then enters and rises in the flow tubing until pressure in the tubing string, or pressure in the tubing string plus pressure of displacement fluid opposing opening of the foot valve, exceeds formation pressure and thus creates pressure differential in the opposite direction for closing the foot valve and opening the head valve. This inaugurates the discharge period during which displacement fluid forms a fluid piston for elevating and expelling the production which has been trapped in the flow tubing. As the production fluid is elevated and expelled, the displacement fluid expands and thereby relieves pressure in the tubing string until said pressure is again exceeded by formation pressure for opening the foot valve and closing the head valve to restart the filling period.

Cyclic operation is thus dependent upon pressure differential inaugurating the filling period,

5 with this pressure differential then automatically decreasing until there is pressure differential in the opposite direction, thereby terminating the filling period and inaugurating the discharge period; and such automatic variation in pressure differential is dependent upon variable factors at each installation.

For example, at each installation the relation between these variable factors must include: (1) admission of displacement fluid at pressure and in quantity sufficient to elevate that volume of production fluid which at the end of the preceding filling period has been trapped above the closed foot valve, and (2) such pressure opposing formation pressure against the foot valve, that the resulting pressure differential will open the foot valve and close the head valve to inaugurate the filling period, with the direction of pressure differential then automatically reversed for closing the foot valve and opening the head valve to inaugurate the discharge period when the volume of production fluid which has entered the tubing string is such that the displacement fluid which is then admitted to the tubing string will elevate this production fluid without blowing through the same and without delay in inaugurating the discharge period.

It is an object of the invention to provide an improved head valve controlling admission of displacement fluid, with desired pressure of displacement fluid exerted against the head valve and opposing opening of the foot valve.

It is a further object of the invention to provide a head valve of sturdy construction and not subject to clogging by sand or the like.

It is a still further object of the invention to proportion the head valve for any desired pressure of displacement fluid opposing opening of the foot valve, and at the same time maintain desired sturdy construction of the head valve.

It is a still further object of the invention to provide for ready interchange of parts for varying the pressure of displacement fluid exerted against the head valve and opposing opening of the foot valve.

Further objects of the invention will be readily understood from the following description of the accompanying drawing, in which:

Fig. 1 is a vertical section through a pump, 50 showing the head valve partly in elevation and partly in axial section.

Figs. 2 and 3 are transverse sections on the lines 2—2 and 3—3 respectively of Fig. 1.

By way of example, the invention is illustrated and described in connection with the pumping of

petroleum wells, the pump being installed in flow tubing A which in the present embodiment of the invention is surrounded by well casing A' so that the annular space D between the tubing and the casing forms a supply conduit for the gas under pressure which constitutes the displacement fluid. The displacement fluid may be supplied to the space D from an upper gas zone of the well or from the earth's surface; and by means of a packer E the annular space D is shut off from the production fluid which enters the well casing from the production zone of the well. This production fluid enters the lower end of the flow tubing A and rises therein, seeking its static or working level.

Valve mechanism comprising a dependently actuated head and foot valve is mounted in the flow tubing. The foot valve B controls admission of production fluid to that portion of the flow tubing which is above its valve seat 1, and the head valve C controls admission of displacement fluid from the annular space D to that portion of the flow tubing which is above the foot valve B.

The valve mechanism B-C is adapted for mounting in the flow tubing A at any desired distance below the packer E, whereby the pump may be operated at a level appreciably below the packer or may be operated at a level adjacent the packer. Means for supplying displacement fluid from the annular space D to the head valve C includes a screen F at the peripheral wall of the flow tubing above the packer E, communicating with a depending conduit G. The lower end of the conduit G communicates with the bore of a guide 2 which is mounted in the lower end of a section 3 of the flow tubing. The valve mechanism B-C is suspended from the bore of the guide 2, in a section 4 of the flow tubing which depends from and is threaded to the section 3 as shown at 5.

Displacement fluid is thus admitted from the annular space D, via the screen F and the conduit G to the bore of the guide 2, and thence via the depending head valve C to the flow tubing A above the foot valve B.

The head valve C comprises a cylinder 10 suspended from and communicating at its upper end with the bore of the guide 2, with a valve sleeve 11 projecting upwardly from a cage 12 and adapted for snug sliding reciprocation on the cylinder 10. When the reciprocating sleeve 11 is at terminal downstroke it uncovers lateral ports 13 in the wall of the cylinder 10 so as to admit displacement fluid to the flow tubing above the foot valve, and when the sleeve 11 is at terminal upstroke it overlies and closes the ports 13 and thus shuts off admission of displacement fluid to the flow tubing.

To prevent the lateral discharge of displacement fluid via the open ports 13 causing undue wear of the surrounding wall of the flow tubing, an annulus 15 of wear-resisting material may be mounted in the bore of the flow tubing in transverse alignment with the ports 13. This annulus may be held in place without it being threaded or accurately machined, by employing a flush joint thread 5 between the tubing sections 3-4, with the usual annular recess at the base of the female thread extended as shown at 5a for reception of the lower portion of the annulus 15 so that it seats on a shoulder 5b at the lower end of this recess, and with the end of the male thread adapted to engage an external annular shoulder 15a which is formed medially of the

length of the annulus 15. The upper portion of the wear-resisting annulus, which is of reduced diameter, telescopes within the bore of the male thread. The joint 5 is preferably positioned so as to mount the annulus 15 with the ports 13 in alignment with the annulus medially of its length.

When the head valve C is closed, pressure of displacement fluid supplied via the conduit G is exerted against the valve and tends to open the valve; and for this purpose a predetermined area of the valve is subject to this pressure. As an instance, a pin 20 projects upwardly from the cage 12 for snug sliding reception in the lower end of the bore of the cylinder 10. The pressure exerted against the pin 20 is dependent upon the pressure of the displacement fluid supplied via the conduit G and the cross-sectional area of the pin; and in practice pins of different cross-sectional area may be interchangeably employed in cylinders 10 adapted for interchangeable suspension from the guide 2 and having bores which at their upper ends are approximately the same diameter as the bore of the guide 2 but which at their lower ends, below the ports 13, vary in diameter for snug sliding reception of pins 20 of different cross-sectional area.

Cylinders 10 may be interchangeably employed by suspending the desired cylinder from the guide 2 by a detachable threaded connection 21; and pins 20 may be interchangeably employed by mounting a pin of desired cross-sectional area on its cage 12 by means of a transverse retaining pin 22 which extends through the base of the cage and the base of the pin.

The foot valve B is adapted for dependent actuation with the head valve C, so that when the sleeve 11 opens the ports 13 the foot valve is closed, and when the sleeve 11 closes the ports 13 the foot valve is open. For this purpose, a valve stem 25 depends from the cage 12, and the foot valve B comprises a valve head 26 suspended from the stem 25 and cooperating with the seat 1 to open or close the foot valve.

In operation, formation pressure tends to open the foot valve B and thereby close the dependently actuated head valve C; and this pressure is opposed by pressure in the flow tubing exerted against the upper face of the foot valve and by pressure of displacement fluid supplied via the conduit G and exerted against the pin 20. By selecting a pin 20 of desired cross-sectional area, and a cylinder 10 which below its ports 13 is adapted for snug sliding reception of the selected pin, these opposing pressures are such that when pressure in the flow tubing is relieved by elevating and expelling a slug of production fluid, pressure differential opens the foot valve and closes the dependently actuated head valve. Production fluid is thus admitted via the open foot valve and rises in the flow tubing, seeking its static or working level.

When pressure of the column of production fluid admitted to the flow tubing, plus pressure of displacement fluid against the pin 20, exceeds formation pressure the foot valve closes, thereby opening the dependently actuated head valve. Displacement fluid is then admitted to the flow tubing via the open ports 13, at pressure and in quantity sufficient to elevate that volume of production fluid which is now trapped in the flow tubing above the closed foot valve. The displacement fluid thus elevates the production fluid as a slug, and discharges the same at the top of the well, thereby relieving pressure in the flow tube.

By relieving pressure in the flow tubing, forma-

tion pressure again exceeds pressure in the flow tubing plus pressure of displacement fluid against the pin 20, thereby reopening the foot valve and closing the head valve for repeating the cycle of operation.

Automatic cyclic operation is thus dependent upon proper pressure of displacement fluid opposing opening of the foot valve; and a head valve C constructed as above described provides a sturdy and reliable construction whereby any desired ratio of pressure area of the head valve to pressure area of the foot valve may be readily provided.

This desired pressure ratio is obtained without balancing pressure of displacement fluid against opposite faces of the head valve, thereby eliminating restricted passages which would be subject to clogging by sand.

The improved construction also eliminates pockets in which sand might collect and prevent desired stroke of the reciprocating valve mechanism B-C, the bore of the sleeve 11 between the cage 12 and the lower end of the cylinder 10 being open via lateral ports 30 which preferably form knife-edges 31 at the bore of the sleeve. Flow of production fluid via the ports 30 thus washes away sand, with no pockets or surfaces on which the sand may accumulate, thereby preventing lodging of sand in the lower end of the sleeve 11 or on the cage 12.

Pressure of displacement fluid is exerted against the pin 20, which is adapted for snug sliding reception in the lower end of the bore of the cylinder 10; but the foot valve B is suspended not from the pin 20 but from the valve stem 25. The stem 25 may thus be of adequate cross-sectional area to insure a sturdy construction while the pin 20 may be appreciably reduced in cross-sectional area without liability of breaking the pin or weakening the head valve structure. Furthermore, both the stationary cylinder 10 and the movable parts 11-20 may be hardened to a degree which will prevent sand galling the relative movable surfaces 10-11 or 10-20, without the resulting relatively brittle construction being liable to break as would be the case if the pin 20 instead of the stem 25 supported the foot valve B.

To prevent sand entering between the sleeve 11 and the cylinder 10, or between the pin 20 and the snugly cooperating lower end of the bore of the cylinder 10, the upper end of the sleeve 11 is preferably beveled for knife-edge sliding engagement with the cylinder 10 as shown at 35, and the lower end of the cylinder 10 preferably forms an annular pocket, tapering for knife-edge sliding engagement with the pin 20 as shown at 36.

The invention has been described as adapted for interchange of pins 20 (of different pressure area) for regulating the pressure differential so as to close the foot valve and open the dependently operated head valve at the end of a desired filling period. The invention is also applicable to a construction such as shown in my aforementioned copending application Ser. No. 224,887, filed August 15, 1938, wherein pressure differential may be regulated by interchanging pins 20 and also by regulating the pressure (in the flow tubing) which is exerted against the upper face of the foot valve B and which cooperates with the pressure area of the pin 20 for establishing the desired pressure differential.

For example, as shown in my aforementioned copending application a valve in the flow tubing (at the earth's surface) may be opened during

the discharge period and then closed for desired time interval during the filling period, thereby increasing the pressure (in the flow tubing) which cooperates with the pressure area of the pin 20 for establishing the desired pressure differential. A pin 20 of relatively small pressure area may thus be employed, since the increased pressure in the flow tubing contributes materially to establishing the desired pressure differential; and a head valve constructed as herein described permits a pin 20 of relatively small area being employed, without liability of breaking the pin and without liability of clogging the head valve.

15 I claim:

1. In valve mechanism for an automatic fluid pressure pump, flow tubing, a cylinder adapted for mounting in the flow tubing and having a lateral discharge port, means for supplying displacement fluid to one end of the cylinder, a cage adapted for reciprocation at the other end of the cylinder, a sleeve on the cage adapted for snug sliding reception on the cylinder for opening or closing the lateral discharge port, the sleeve having lateral ports between the cage and the proximate end of the cylinder, said ports having knife-edges at the bore of the sleeve, a pin projecting from the cage and adapted for snug sliding reception in the bore of the cylinder, a valve stem projecting from the opposite face of the cage, a valve seat adapted for mounting in the bore of the flow tubing, and a valve head on the valve stem cooperating with the valve seat for controlling flow of production fluid via the bore of the flow tubing.

2. In a valve mechanism for an automatic fluid pressure pump, flow tubing, a cylinder adapted for mounting in the flow tubing and having a lateral discharge port, means for supplying displacement fluid to one end of the cylinder, a cage adapted for reciprocation at the other end of the cylinder, a sleeve on the cage adapted for snug sliding reception on the cylinder for opening or closing the lateral discharge port, the bore of the sleeve being open to the exterior thereof between the cage and the proximate end of the cylinder, a pin projecting from the cage and adapted for snug sliding reception in the bore of the cylinder, a valve stem projecting from the opposite face of the cage, a valve seat adapted for mounting in the bore of the flow tubing, and a valve head on the valve stem cooperating with the valve seat for controlling flow of production fluid via the bore of the flow tubing.

3. In a valve mechanism for an automatic fluid pressure pump, flow tubing, a cylinder adapted for mounting in the flow tubing and having a lateral discharge port, means for supplying displacement fluid to one end of the cylinder, a cage adapted for reciprocation at the other end of the cylinder, a sleeve on the cage adapted for snug sliding reception on the cylinder for opening or closing the lateral discharge port, a pin projecting from the cage and adapted for snug sliding reception in the bore of the cylinder, a valve stem projecting from the opposite face of the cage, a valve seat adapted for mounting in the bore of the flow tubing, and a valve head on the valve stem cooperating with the valve seat for controlling flow of production fluid via the bore of the flow tubing.

4. In a valve mechanism for an automatic fluid pressure pump, flow tubing, a cylinder adapted for mounting in the flow tubing and having a lateral discharge port, means for sup-

plying displacement fluid to one end of the cylinder, a sleeve adapted for snug sliding reception on the cylinder for opening or closing the lateral discharge port, a pin fixed relative to the sleeve and adapted for snug sliding reception in the bore of the cylinder, a valve stem projecting from the sleeve, a valve seat adapted for mounting in the bore of the flow tubing, and a valve head on the valve stem cooperating with the valve seat for controlling flow of production fluid via the bore of the flow tubing.

5. In a valve mechanism for an automatic fluid pressure pump, flow tubing, a cylinder adapted for mounting in the flow tubing and having a lateral discharge port and a restricted bore at

one end of the cylinder beyond the discharge port, means for supplying displacement fluid to the opposite end of the cylinder, a sleeve adapted for snug sliding reception on the cylinder for opening or closing the lateral discharge port, a pin fixed relative to the sleeve and adapted for snug sliding reception in the restricted bore of the cylinder, a valve stem projecting from the sleeve, a valve seat adapted for mounting in the bore of the flow tubing, and a valve head on the valve stem cooperating with the valve seat for controlling flow of production fluid via the bore of the flow tubing.
